UNITED STATES PATENT OFFICE.

ROSWELL A. MOORE AND WILLIAM F. MURTHA, OF WATERBURY, CONNECTICUT, ASSIGNORS TO WATERBURY BUCKLE CO., OF WATERBURY, CONNECTICUT, A CORPORATION.

BUCKLE.

Application filed November 4, 1925. Serial No. 66,712.

To all whom it may concern:

Be it known that we, ROSWELL A. MOORE and WILLIAM F. MURTHA, citizens of the United States, residing at Waterbury, in 5 the county of New Haven and State of Connecticut, have invented a new and useful Improvement in Buckles; and we do hereby declare the following, when taken in connection with the accompanying drawings 10 and the characters of reference marked thereon, to be a full, clear, and exact description of the same, and which said drawings constitute part of this application, and represent, in—

15 Fig. 1 a front view of a buckle constructed in accordance with our invention and shown as engaged with a piece of webbing.

Fig. 2 a sectional view on the line 2—2 of Fig. 1.

20 Fig. 3 a front view of the buckle-frame, with the lever removed.

Fig. 4 a sectional view on the line 4—4 of Fig. 3.

This invention relates to improvement in 25 buckles particularly adapted for use on suspenders and garters and of the so-called "rustless" type. In buckles of this type, the web has been attached to the frame by forming the frame with pointed prongs beneath 30 which the web has been inserted and the prongs pressed against the web. The object of this invention is to form the buckle with grippers having heads which increase their holding capacity by increasing the area of 35 contact between the grippers and the web, and the invention consists in the construction as hereinafter described and particularly recited in the claims.

In carrying out our invention, we form 40 the buckle-frame from sheet-metal, comprising a plate 5 and a top-bar 6 upon which the lever 7 is pivoted in the usual manner, this lever having downwardly and rearwardly extending gripping-teeth 8. Preferably, the sides of the frame will be bent to 45 form reinforcing flanges 9, and these flanges may extend forward or rearward. Struck out from the plate 5 are a series of grippers

10, and these grippers have heads 11 which are cupped, as shown in Fig. 4 of the drawings, so as to form a gripping-edge entirely around the head. 50

The end 12 of a strip of webbing is inserted between the grippers and the plate 5, as shown in Figs. 2 and 4 of the drawings, 55 and the grippers are then pressed rearward against the webbing, and the edges of the heads bite into the webbing, so as to obtain a strong grip thereon, and the extent of this gripping surface is greater than the width 60 of the webbing.

The sides of the heads being wider than the necks or lower portions of the grippers, the webbing is "bunched," so to speak, beneath the projecting heads and, consequently, forms a resistance against pulling out. 65 The grippers might be likened to anchors, the sides of the heads forming flukes which hold the web, these flukes being embedded in the body of the web itself and, therefore, do 70 not depend entirely upon their compression against the web.

After the webbing is connected with the buckle-frame, it is passed from front to rear, over the upper edge of the plate and beneath 75 the top-bar, thence downward through a loop 13 and upward over the grippers and rearward through the opening below the top-bar, over which it is deflected by the 80 teeth 8 of the lever 7.

With this construction, the end of the web is firmly attached to the buckle, without increasing the amount of webbing employed for this purpose, and the web is so firmly gripped as to withstand the strain which is 85 placed upon it, whether the grippers project forward or rearward from the buckle-plate.

We claim:

1. A buckle having a frame comprising a 90 plate and a top-bar, a lever pivotally connected with the top-bar, the plate formed with grippers each comprising a neck and a head struck out from it, the heads being wider than the necks.

2. A buckle having a frame comprising a 95 plate and a top-bar, a lever pivotally con-

nected with the top-bar, the plate formed with grippers each comprising a neck and a head struck out from it the said heads being wider than the necks and cupped.

3. The combination with a buckle-frame, comprising a plate and a top-bar, a lever pivotally connected with the top-bar, grippers each comprising a neck and a head struck out from the plate the heads being

wider than the necks, combined with a web 10 inserted between the grippers and the plate, thence passing downward, and thence upward and beneath the top-bar in position to be engaged and deflected by the lever.

In testimony whereof, we have signed 15 this specification.

ROSWELL A. MOORE.
WILLIAM F. MURTHA.
